(57) **CLAIM**

The ornamental design for an external mounted free fall handle, as shown and described.

DESCRIPTION

FIG. 1 is a top view of an external mount free fall handle showing my new design.

FIG. 2 is a side view thereof.

FIG. 3 is an end view thereof.

FIG. 4 is a front perspective view thereof shown in a mounted configuration with the handle bail in the lifting position.

FIG. 5 is a front perspective view thereof shown in a mounted configuration with the handle bail in the unrestrained position; and,

FIG. 6 is a rear perspective view thereof shown in a mounted configuration with the handle bail in the lifting position.

The broken lines showing in the figures are included for the purpose of illustrating environmental use only and form no part of the claimed design.
